UNITED STATES PATENT OFFICE.

PHILIP MUELLER, OF DECATUR, ILLINOIS, ASSIGNOR TO H. MUELLER MANUFACTURING CO., OF DECATUR, ILLINOIS, A CORPORATION OF ILLINOIS.

BATH OR BASIN FITTING.

1,026,632.

Specification of Letters Patent. Patented May 14, 1912.

Application filed October 31, 1908. Serial No. 460,437.

To all whom it may concern:

Be it known that I, PHILIP MUELLER, a citizen of the United States, and resident of Decatur, Macon county, State of Illinois, 5 have invented certain new and useful Improvements in Bath or Basin Fittings; and my preferred manner of carrying out the invention is set forth in the following full, clear, and exact description, terminating 10 with claims particularly specifying the novelty.

This invention relates to baths and closets and more especially to bath and basin fittings, and the object of the same is to facilitate 15 the attachment of the fittings to a bath tub or lavatory, and the coupling of a single or compound faucet thereto.

Another object is to lessen the labor and expense of manufacture by reducing the 20 number of parts to a minimum yet without sacrificing the utility of the fitting or producing difficulty with its use in limited quarters.

To this end the invention consists in a fitting 25 which comprises a supply pipe having its upper extremity enlarged, greater than the diameter of the hole through the lavatory wall, and its body beyond said enlargement provided for limited entrance into said 30 hole, and interiorly screw threaded for the receipt of a connecting thimble, said enlargement or flange being irremovable off the upper extremity of said supply pipe, and constituting an outer clamping means against 35 the fixture wall, and a detachable coupling between the faucet shank and the inner end of the supply pipe. The following specification sets forth certain embodiments of this idea in one of its forms, and a modification 40 thereof. In all forms however, the outer flange is integral with the supply and irre- 45 movable therefrom.

In the drawings forming a part of this specification, Figure 1 is a sectional view 45 showing one form of this fitting clamped to a lavatory wall, and a supply pipe broken away adjacent its bend. Fig. 2 is a sectional view of the same fitting showing the supply pipe having a threaded outer end and a vari- 50 ance in the thimble. Fig. 3 is a sectional view of the same form showing the supply pipe broken adjacent its bend, and a variance in the coupling end of the thimble.

In setting up the usual bath tub or other

lavatory member and its fittings the general 55 practice is to bring the tub into the position it will occupy when the job is completed, connecting the supply with the service either before or after the tub is so located, then pass the tail piece of the faucet through the 60 hole in the tub wall and finally make the coupling between this tail piece and the supply pipe at a point outside the tub wall and beneath and close under its rim in cramped quarters where said rim stands. Quite close 65 to the wall it is often difficult for the plumber to make this connection because the space is limited, the light is poor, and he finds much difficulty in using tools to good ad- 70 vantage.

By the present invention, I do away with the necessity of having any joint or connection in the supply pipe at a point exterior to the tub or like wall dispensing with the use of tools after the tub is placed. The connection with the supply is usually a wipe joint or slip joint at or below the floor line where the workman has sufficient room to 75 install same, due to the outward contour of 80 the tub wall.

Referring to the accompanying drawings the numeral 1 designates a supply pipe continuous from its connection with a joint at the floor upward to and partly into the aperture 18 of the tub or other similar wall, 85 and continuous and integral from such connections until it passes to or through aperture 18 as at 32, this depending somewhat on the thickness of the wall 4.

Near the outlet end 32 of the supply pipe 90 is a circumferential collar or flange 10^a of greater diameter than the aperture 18, and made with a smooth face to fit closely against the wall through which said aperture is made. The projecting outlet end 18 is 95 larger than the rest of the pipe 1 and is made frusto-conical as shown, its extreme end being smaller than the aperture so that when setting the pipe in a dark or restricted place, this frusto-conical end can be moved about in contact with the wall of the tub or basin until it enters the aperture. The end 32 thus becomes a guide to the workman in adjusting the fixture.

The thimble 12 in Fig. 1 has an exterior straight or tapered thread 26 which enters the aperture and takes onto the interior thread of the supply pipe within the en-

2
larged portion 10^a. This thread 26 may be on the same plane with the exterior tapered thread and continues with it, being straight or parallel on the portion on which a flange 14 is mounted and tapered for receiving the supply pipe. At the inward extremity of the thimble 12 and the supply pipe 1 is located a packing 28 which when compressed completes the joint between the supply and thimble; on its inward extremity the thimble bears a shoulder 23 which extends around its entire periphery. The coupling nut 21 has a shoulder 20 which takes on back of the shoulder 23, and the coupling nut in turn takes on to the threaded portion of the bath cock shank 22. Within the thimble 12 and adjacent its innermost extremity is a valve receiving chamber 19 in which is located the Fuller valve 30 which is actuated in a well known manner, opening and closing off the flow of water by seating against the end of faucet shank 22. Adjacent the valve chamber 19 where the passageway of the thimble assumes a diameter near that of the supply pipe are located two inwardly projecting lugs 25 whereby a wrench may be inserted when the cock is removed, and the thimble 12 tightened, loosened, or adjusted in its relations to the connecting supply pipe.

In Fig. 2, supply pipe 1 is shown with secondary joint 2^a and is exteriorly threaded at its lower extremity. The collar or flange 10^a is similar in its make up as Fig. 1 except the provision of a circumferential groove 31 which is provided to lessen cost in manufacture and to accommodate the varying lengths in the entering end of thimble 12 as will be hereinafter shown. The thimble 40 however is provided with a tapered thread on its end connecting with the supply as 29^a and with a straight thread on a higher plane on which is mounted the flange 14, said flange is provided with a smooth clear portion around its entire inner surface as 13 which is adapted to pass over a smooth portion of the shouldered surface as at 12^a. This further serves the purpose of covering from view any threads which would otherwise be exposed when the nut assumes its normal position. Flange 14 bears hexagonal or flat surfaces 15 for the application of wrench in setting up or adjusting. The thimble 12 at its inner extremity carries the shoulder 23 and bears the inner valve chamber 19 as above described. The lugs 25 are here mounted on the wall of the chamber 19 and project inwardly; these are for wrench hold purposes. Between these lugs and the inlet extremity of the thimble the passageway is diminished as in Fig. 2 to correspond with that in the supply pipe.

In Fig. 3, the features as there set out correspond with those in Fig. 1, except that the outlet extremity of the thimble bears exte-

rior threads 27^a for the receipt of the coupling nut 21, or is so far as the connecting of the nut is concerned, the reverse of Fig. 1.

In setting up this device in connection with a bath tub the supply is brought to the outside of the tub and the projection 32 of the supply enters the apertures 18 until the flange face 11 comes against the wall of the tub around the aperture; the flange 14 is run back on the thimble 12 toward the shoulder 23 so far as the space 13 will allow it. The thimble is then brought from the inside of the tub, the packing is placed in the supply pipe as 28 and the thimble is then screwed into the flange until a joint is formed. The flange is then brought toward the wall of the tub and tightened until the fitting assumes the fixed position relative to the tub whereupon the bath cock may be attached in the manner well known, the entire operation being performed from the inside of the tub. The outer connection of the supply is made in the usual manner.

What I claim as new is:

1. In a lavatory fitting, a supply pipe 90 having an enlarged outlet provided with an annular flange having a flat face on one side to bear against the outer wall of a lavatory fitting, and an integral projection from said face larger than said supply pipe 95 extending into an aperture in said lavatory member, said projection having a screw threaded opening continuous with the bore of the water pipe, a thimble screwed into the threaded opening of said projection on the 100 water pipe, said thimble having means on its opposite end for the attachment of a cock, and a clamping member threaded onto the intermediate portion of said thimble adapted to engage the inner wall of the 105 lavatory member, and in connection with the flange on said supply pipe secure the latter and the thimble in fixed position.

2. In a lavatory fitting, a supply pipe 110 having a flange around its upper end larger than the body of the pipe and integral therewith and adapted to bear against the outer wall of a lavatory member, an annular extension beyond the flange adapted to enter the aperture in said wall and having an interiorly threaded opening within the flange and extension, an exteriorly threaded thimble bearing a clamping member adapted to engage the inner wall of said lavatory member, and means on the thimble to receive a 115 valve.

3. In a lavatory fitting comprising a supply pipe having its upper end flanged, said flange being greater than the body of the pipe and the aperture of the wall of a lavatory member and integral with the pipe, an extension beyond the flange adapted to enter the aperture, interior threads within the flange of greater diameter than the bore of the pipe and a thimble bearing a clamping 120 valve.

- member adapted to engage said threads from within said member, said clamping member engaging the inner wall thereof, a shoulder between the engaging threads of the thimble and the threads bearing the clamping member, and means in the flange beyond its thread to allow for variation in the length of the thimble.
4. In a lavatory fitting comprising a supply pipe having its upper end flanged, said flange being greater than the body of the pipe and the aperture of the wall of a lavatory member and integral with the pipe, an extension beyond the flange adapted to enter the aperture, interior threads within the flange of greater diameter than the bore of the pipe and a thimble bearing a clamping member adapted to engage said threads from within said member, said clamping member engaging the inner wall thereof, a shoulder between the engaging threads of the thimble and the threads bearing the clamping member, a chamber in the flange beyond the thimble, a valve chamber within the thimble of greater diameter than the supply pipe adapted to receive a valve and threads on the exterior surface of the thimble adjacent its inner end for receiving the coupling nut of a cock.
5. In a lavatory fitting comprising a sup-

ply pipe having its upper end flanged, said flange being greater than the body of the pipe and the aperture of the wall of a lavatory member and integral with the pipe, an extension beyond the flange adapted to enter the aperture, interior threads within the flange of greater diameter than the bore of the pipe and a thimble bearing a clamping member adapted to engage said threads from within said member, a shoulder between the engaging threads of the thimble and the threads bearing the clamping member, a chamber in the flange beyond the thimble for allowing the extension of the thimble, a valve chamber within the thimble of greater diameter than the supply pipe adapted to receive a valve and threads on the exterior surface of the thimble adjacent its inner end for receiving the coupling nut of a cock.

In testimony whereof, I have hereunto subscribed my signature, this 26th day of October, A. D. 1908.

PHILIP MUELLER.
